CARRIAGE SUPPORTED BATCH MIXER

Fred J. Machovec, 2595 Las Lunas, Pasadena, Calif.

Filed Feb. 25, 1960, Ser. No. 59,526

Term of patent 3½ years

(Cl. D55—5)

FIGURE 1 is a perspective view of a carriage supported batch mixer incorporating the new design as viewed from one rear corner;

FIGURE 2 is a top plan view; and

FIGURE 3 is a side elevation view as viewed from the far side of FIGURE 1.

The dominant features of my design reside in the portions shown in full lines.

I claim:

The ornamental design for a carriage supported batch mixer, as shown and described.
